DESIGN FOR A CURL COMB

Nathan L. Solomon, Mount Vernon, N. Y.

Application December 6, 1938, Serial No. 81,666

Term of patent 14 years

To all whom it may concern:

Be it known that I, Nathan L. Solomon, a citizen of the United States, residing in the city of Mount Vernon, county of Westchester, and State of New York, have invented a new, original, and ornamental Design for Curl Comb, of which the following is a specification, reference being had to the accompanying drawing, forming a part thereof, in which:

Fig. 1 is a side view of my curl comb showing my new design,

Fig. 2 is a plan view of Fig. 1.

I claim:

The ornamental design for a curl comb, substantially as shown.

NATHAN L. SOLOMON.
